(57) **CLAIM**

The ornamental design for a urinal seal, as shown and described.

DESCRIPTION

This design patent application is related to Design Patent applications Ser. Nos. 29/353,290, 29/353,294 and 29/353,297 and also Utility Patent application Ser. No. 12/683,331 which are filed on even date herewith.

FIG. 1 is a rear perspective view of a urinal seal;

FIG. 2 is a side view thereof;

FIG. 3 is a top view thereof;

FIG. 4 is a bottom view thereof;

FIG. 5 is a cross section view along Line 5-5 as shown in FIG. 2 thereof.

FIG. 6 is a rear perspective view of a urinal seal;

FIG. 7 is a side view thereof;

FIG. 8 is a top view thereof;

FIG. 9 is a bottom view thereof;

FIG. 10 is a cross section view along Line 10-10 as shown in FIG. 7 thereof;

FIG. 11 is a rear perspective view of a urinal seal;

FIG. 12 is a side view thereof;

FIG. 13 is a top view thereof;

FIG. 14 is a rear view thereof;

FIG. 15 is a cross section view along Line 15-15 as shown in FIG. 12 thereof;

FIG. 16 is a rear perspective of a urinal seal;

FIG. 17 is a side view thereof;

FIG. 18 is a top view thereof;

FIG. 19 is a rear view thereof; and,

FIG. 20 is a sectional cross section view along Line 20-20 as shown in FIG. 17 thereof.
